UNITED STATES PATENT OFFICE.

ALLAN CAMERON SARGENT, OF GRANITEVILLE, MASSACHUSETTS.

CARBURETER.

SPECIFICATION forming part of Letters Patent No. 680,941, dated August 20, 1901.

Application filed April 16, 1901. Serial No. 56,099. (No model.)

To all whom it may concern:

Be it known that I, ALLAN CAMERON SARGENT, a citizen of the United States, residing at Graniteville, in the county of Middlesex, State of Massachusetts, have invented a certain new and useful Improvement in Carbureters, of which the following is a specification, reference being had therein to the accompanying drawings.

10 One of the main objects of my invention is to produce a simple and efficient carbureting apparatus, more especially designed for use in automobiles, although equally adapted to the enrichment of air or gas for illuminating purposes, and to other analogous uses.

The invention will first be described in connection with the accompanying drawings, the latter illustrating the best form in which I have thus far embodied the invention, after 20 which its essential characteristics will be particularly pointed out and distinctly defined in the claims at the close of this specification.

In the drawings, Figure 1 is a middle vertical longitudinal section through the apparatus. Fig. 2 is an end view of the same, taken from the right-hand side in Fig. 1, the shell of the float-chamber being partially broken away. Fig. 3 is a top view partially in section. Fig. 4 is a section on the line 4-4 25 of Fig. 1. Fig. 5 is a horizontal section of the mixing-valve. Fig. 6 is a plan of the same.

In general my carbureter may be characterized as mainly comprising three chambers.

In the drawings the numeral 1 designates the lower main chamber, the same being designed to hold a quantity of liquid gasoline. This last enters the chamber through an opening 2, communicating with a float or supply chamber 3, the said opening being provided 30 with a wire screen 4. In the supply-chamber is located a float 5, which presses upward against a knob or enlargement 6 at the lower end of the stem 7 of the needle-valve 8. The needle-valve 8 is located in a gasoline-inlet 40 pipe 9 and co-operates with a valve-seat 10 therein. The pipe 9 terminates in a removable cap 11, whereby access may be had to free the needle-valve in case it fails to separate from its seat on the descent of the float. 45 Gasoline is supplied to the pipe 9 through a lateral connection 12. This described construction, whereby I obtain a separation of

the supply or float chamber from the gasoline-receptacle, their connection by a submerged opening, and the interposition between them of the screen 4, not only prevents foreign substances from passing from one to the other, but quiets the relatively small body of gasoline in the float-chamber, which has only a very small area of free surface— 55 namely, the annular space between the float and the walls of the chamber. Thereby the action of the float and needle valve is rendered very regular. As will of course be understood, peculiar conditions are present 60 when a carbureter is employed in a motor-vehicle. The jarring, tilting, and irregular movements of the latter interfere with the satisfactory working of many devices that may be successfully employed for stationary 70 use. It is my especial purpose to avoid many of the difficulties hitherto encountered in adapting carbureters to motor-vehicles.

Above the gasoline-receptacle and completely separated therefrom, except through 75 the communication established by a series of wick-tubes 13, is located the vapor-chamber 14. Were the chambers separated from each other simply by a perforated partition or the like, in such case any considerable degree of 80 inclination or violent motion of the vehicle on which the carbureter is mounted would be apt to cause the gasoline to flood the vapor-chamber. By making the wick-tubes, which constitute the only means of communication 85 between the gasoline and vapor-chambers, of considerable length no motion or inclination of the carbureter occasioned by practical and ordinary use is sufficient to throw liquid gasoline into the vapor-chamber. 90

Each of the wick-tubes 13 just described extends substantially across from side to side of the vapor-chamber and each contains a broad wick designated 15. An advantageous arrangement of such wicks is that of endless bands each passing over one of a series of rods 16, fixed at the top of the vapor chamber, and under one of a series of rods 17, fixed at or near the bottom of the gasoline-receptacle, the corresponding rods of each series being 95 located in line with the wick-tubes themselves, so that the parallel portions of each web run through the same wick-tube. The general function of the wicks, as will be un- 100

derstood, is to take up gasoline from the lower receptacle and convey the same by capillary action into the vapor-chamber, where such gasoline is held in the meshes of the 5 wicks in a finely-subdivided state, ready to be withdrawn as vapor by the aspiration of the engine.

The wicks constitute porous diaphragms extending across the vapor-chamber and 10 through which the current of air or gas to be carbureted is caused to pass. This insures that all the air introduced into the vapor-chamber shall pass through the wicks and become thoroughly charged with vapor before 15 being withdrawn from the vapor-chamber, and at the same time the arrangement permits of the freest possible movement of air consistent with this result.

To permit admission of air into the vapor-chamber, an inlet-pipe 20 is provided at one 20 end thereof, the said inlet-pipe being furnished with a check-valve 21, opening inwardly. The inlet-pipe 20 has a diaphragm 22, fixed within it near its inner end, the said 25 diaphragm having a central perforation through which projects the stem 23 of the valve and having also surrounding perforations 24 for the passage of air. On the stem 23 is fixed a second diaphragm 25, having 30 similar perforations. Between the two diaphragms is confined a spiral spring 26 of sufficient strength to hold the valve 20 upon its seat, except when a partial vacuum is produced in the vapor-chamber.

35 The vapor-outlet pipe 27 is located opposite the air-inlet valve and is provided with the usual screens 271 to prevent firing back. The said pipe leads to a mixing-valve 28, having an air-inlet 29 and an outlet 30, leading to the 40 engine. The mixing-valve is a three-way valve, the plug thereof being cut away at one side, as indicated at 31. In the position of the said plug which is shown in Fig. 3 only vapor will be taken into the engine, the air-inlet 29 being entirely closed. In the position shown in Fig. 5 only air will be taken in, the 45 vapor-inlet being completely shut. In intermediate positions of the plug any desired mixture of air and vapor may be obtained.

50 Fig. 32, Fig. 6, is the handle for operating the mixing-valve.

The gasoline in the lower receptacle may be heated by the exhaust from the engine or the like, introduced through the loop of pipe 33, 55 located in the lower part of the receptacle, thus accelerating the evaporation of the gasoline.

What I claim is—

1. A carbureter comprising, essentially, a 60 gasoline-chamber, a vapor-chamber above the

same having an air-inlet at one end thereof and a carbureted-air outlet at the other end thereof, wick-tubes of considerable length extending vertically between said chambers, and wicks extending through said wick-tubes 65 into said chambers and extending across the entire width of the vapor-chamber to form a series of transverse diaphragms through which the air must penetrate on its way from the inlet to the outlet. 70

2. A carbureter comprising, essentially, a gasoline-chamber, a vapor-chamber above the same having an air-inlet at one end thereof and a carbureted-air outlet at the other end thereof, wick-tubes connecting said chambers, 75 rods in both chambers in line with the respective wick-tubes, and endless wicks extended respectively through the respective wick-tubes and supported by the rods in line therewith, the said wicks extending across the entire width of the vapor-chamber to form a series of double transverse diaphragms through which the air must penetrate on its way from the inlet to the outlet. 80

3. A carbureter comprising, essentially, a gasoline-chamber, a vapor-chamber above the same having at one end thereof an air-inlet provided with a normally-closed spring-actuated valve and at the other end thereof having a carbureted-air outlet, wick-tubes of considerable length extending vertically between said chambers, and wicks extending through said wick-tubes into said chambers and extending across the entire width of the vapor-chamber to form a series of transverse dia- 95 phragms through which the air must penetrate on its way from the inlet to the outlet. 90

4. A carbureter comprising, essentially, a separate float-chamber, a submerged opening between the same and the gasoline-chamber, 100 a float in said float-chamber, a valve for admitting gasoline operated by the float, a gasoline-chamber, a vapor-chamber above the same having an air-inlet at one end thereof and a carbureted-air outlet at the other end 105 thereof, wick-tubes of considerable length extending vertically between said chambers, and wicks extending through said wick-tubes into said chambers and extending across the entire width of the vapor-chamber to form a 110 series of transverse diaphragms through which the air must penetrate on its way from the inlet to the outlet.

In testimony whereof I affix my signature in presence of two witnesses.

ALLAN CAMERON SARGENT.
